VENT STRUCTURE FOR ELECTROLYTIC
CONDENSERS AND THE LIKE

James Henry Cotton, London, England, assignor,
by mesne assignments, to Cornell-Dubilier Electric
Corporation, a corporation of Delaware

Application August 18, 1938, Serial No. 225,524
In Great Britain October 30, 1937

7 Claims. (Cl. 220—44)

The present invention relates to improvements in vent structures associated with containers for relieving a container of excess gas or vapors developed therein as a result of temperature changes and other causes.

More specifically, the invention is concerned with self-closing relief vents for the containers of electric condensers, in particular, although not necessarily, electrolytic condensers which will normally act to seal the container but will permit the escape of a gas or vapor when the pressure within the container exceeds a predetermined value.

It has already been proposed in such vent arrangements to close an opening in the condenser container by a diaphragm or membrane of an elastic material such as rubber provided with one or more pin-hole punctures or incisions normally closed by reason of the elasticity of the material, the diaphragm being capable of distending when the gas and/or vapor pressure within the container exceeds a predetermined value so that the puncture or punctures open to permit the gas and/or vapors to escape.

While such vent arrangements normally operate satisfactorily, it is often found, particularly when they are employed for wet electrolytic condensers comprising a liquid electrolyte filling the container, that the puncture or incision tends to become clogged with electrolyte or other foreign matter so that it no longer acts properly as a valve. This may cause in the case for example of an electrolytic condenser undesirable leakage of the electrolyte or liquid constituents thereof, due to the liquid being forced through crevices by the very high pressures which may be set up within the condenser during operation, resulting in a shorter life of the condenser owing to loss or evaporation of electrolyte, the production low resistance paths between the terminals and other defects and drawbacks well understood by those skilled in the art.

Accordingly, an object of the invention is to provide an improved self-closing relief vent of the above general character for electrolytic condensers or other devices subject to internal excess gas pressure by which clogging of the vent opening or puncture by foreign matter and the defects and drawbacks associated therewith are substantially avoided.

Further objects and aspects of the invention will become more apparent from the following detailed description taken with reference to the accompanying drawing forming part of this specification and wherein,

Figure 1 is a vertical cross-sectional view through an electrolytic condenser of the wet type with the new vent construction according to the invention embodied therein,

5 Figure 2 is a partial view of Figure 1 showing a modification thereof,

Figure 3 is a further partial view illustrating a further modification of the invention.

Similar reference numerals identify similar parts in the several views of the drawing.

Referring more particularly to Figure 1, the condenser shown comprises a metallic container 10 of cylindrical or other shape having its upper open end closed in a liquid tight manner by an outwardly arched cap 11 overlying a diaphragm 12 of elastic material such as rubber or the like and secured to the container by spinning or rolling in a known manner the edge of the container over the outer rim or flange of the cap 11. In this manner the outer rim of the diaphragm acts as a gasket to effect a liquid tight seal for the container, while the inner portion serves as a vent in the manner described hereafter. Item 13 represents a filmed anode of any desired configuration such as in the form of a pleated metal sheet secured to a central supporting rod or riser 14, as shown and described in U. S. patent application 53,567, filed December 7, 1935, in the name of Paul McKnight Deeley. The riser 14 is passed through a central opening of a resilient plug of rubber or the like forced through the outwardly threaded neck 16 of the container with either the plug or opening of the neck or both being of a flaring or conical shape to produce a liquid tight seal and to hold the anode 13 in a central position within the container. The projecting end of the rod 14 serves as a connecting terminal for the anode and for this purpose may be provided with a connecting lug 17 or the like

20 in a manner well known. Both the anode 13 and container 10 may consist of aluminum or any other suitable metal, at least the anode metal being of the film forming type. Item 18 represents a perforated insulating cylinder or spacer of Celluloid or other suitable material placed between the anode and inner wall of the container to avoid direct contact between the anode and the container which latter in the example illustrated serves as the cathode of the condenser in accordance with known practice. The container

25 is filled with a suitable electrolyte to a sufficient level as indicated at 19 and the condenser is preferably mounted in an inverted position such as shown in the drawing upon a platform or 30 chassis by means of a nut (not shown) engaging

the outer threads of the neck 16 in a manner well known in present day practice.

The inner section of the diaphragm 12 serves as a vent for allowing excess gas or vapors developed within the condenser to escape to the outside and for this purpose is provided with one or more punctures or incisions normally closed by reason of the elasticity of the material. If excess gas pressure is developed within the container due to heat generated during the operation of the condenser the diaphragm is distended outwardly toward the cap 11, thereby opening the puncture or incision and allowing the excess gases or vapor to escape to the outside through the escape holes 21 in the cap 11.

The diaphragm 12 is preferably provided with an annular collar or spacer 23 which may be integral therewith as shown surrounding the punctured center section, whereby with increasing gas pressure at first the diaphragm is distended in its entirety until stopped when the collar 23 engages the cap 11, whereupon with further increase of pressure only the central punctured section is allowed to distend further and to open the pin-hole or incision and to allow the excess gas to escape therethrough. In order to further improve the operation and to accurately predetermine the pressure at which the vent opens the central section of the diaphragm is preferably of a lesser thickness than its outer portion as shown in Figure 3. Further details regarding this construction are found in the above co-pending application and a further application Serial No. 81,252, filed May 22, 1936, by the same applicant.

According to the improvement of the present invention, there is provided at least one sharply pointed or tapered member, referred to as a pin for the purpose of this specification, being so disposed relatively to the diaphragm that its point penetrates the diaphragm either as the diaphragm distends due to gas pressure within the container or normally so that it projects through a punctured hole in the diaphragm. The latter arrangement is shown in Figure 1 wherein an extension 20 of the riser 14 having a sharply pointed end normally passes through the central pin-hole or incision in the diaphragm 12 thereby preventing clogging of the latter by foreign matter and ensuring proper functioning upon the production of excess pressure and distension of the diaphragm as indicated by dotted lines in the drawing.

When the or each pointed member is arranged so as to puncture the diaphragm only when it distends, that is where the point is normally in line with the diaphragm surface, the diaphragm may be initially unpunctured so as to seal the container during transport, the diaphragm only being punctured when it first distends during operation of the condenser. Alternatively, the diaphragm may be provided with one or more punctures normally closed by reason of the elasticity of the material, at least one member being in alignment with the puncture so as to pass through it when the diaphragm distends and thus prevent clogging of the puncture hole.

An arrangement of the latter type is shown in Figure 2 wherein the pointed member has the form of a rivet 22 secured to the cap 11 with its point normally in line with or just touching the central puncture of the diaphragm 12. Thus, if excess pressure is developed within the container, the diaphragm will distend as indicated

in dotted lines, whereby any foreign matter such as electrolyte, dust particles or the like which may have entered the puncture hole previously will be dislodged by the pointed member entering the puncture hole thereby ensuring ready escape of the excess gas or vapor from the interior of the container to the outside.

If desirable, additional means such as a spring may be provided for assisting in returning the diaphragm to its normal position after it has distended to permit the escape of gas from within the container, such means preferably being disposed between the diaphragm and the outer apertured cap or cover. An arrangement of this type is shown in Figure 3 wherein a coil spring 24 is placed between the central section of the diaphragm 12 and the cap 11. This spring in the embodiment illustrated has one of its ends formed into a sharp point and bent inwardly and axially to serve as a pointed member or pin co-operating with the puncture hole in the manner described. The annular rim or spacer 23 in this case serves as a positioning means to hold the spring 24 in proper position. Furthermore, in the example illustrated the central section of the diaphragm is of lesser thickness than its outer portion for the purpose described hereinabove.

The pointed member or pin 22 in Figure 2 may also be formed integral with the cap 11 as by extrusion or in any other suitable manner so that normally at least one pin is substantially perpendicular to the diaphragm with its point a short distance from the outside surface thereof and preferably in alignment with the puncture, or normally passing through the puncture hole in the diaphragm. Thus when, owing to excess pressure within the container, the diaphragm is distended the action of the pin will be to dislodge or penetrate through any solid material such as electrolyte, dust particles, etc., which may have entered into the pin-hole puncture or incision or may have accumulated around the puncture, thereby insuring that there is an adequate opening through which the gas can escape. When the gases have escaped the diaphragm returns to its normal position in which it is clear of the end of the pin as in the embodiments according to Figures 2 and 3 or initially penetrates the pin as in the embodiment according to Figure 1.

The diaphragm may be formed and mounted in the container in any desired manner, particularly desirable arrangements being those shown and described in greater detail in the above mentioned co-pending applications.

The arrangement described and illustrated in application Serial No. 81,252, filed May 22, 1936, in which the spacing member in the form of a closed ring or flange is provided between the diaphragm and an outer cap, as shown also in the accompanying drawing (collar 23) and is fixed to or formed integral with either the diaphragm or cap, is particularly suitable when a spring is provided between the diaphragm and the cap as this spacing member may serve to position a suitable helical spring and to prevent the latter from being displaced during service as shown and described.

As is understood, the pin may be supported by the anode (Figure 1) or any other part of the condenser or by the cap 11 as shown in Figure 2 or a special member such as a disc or the like arranged for this purpose underneath the diaphragm or a coil spring or other additional resil-

ient spacer provided in the manner and for the purpose described.

While in the constructions according to Figures 2 and 3 wherein the pin or pointed member is provided at the outer surface of the diaphragm 12 and serves primarily to dislodge foreign matter accumulated within or around the puncture hole during the distension of the diaphragm, the operation according to Figure 1 wherein the pin or pointed member is arranged at the inner end of the diaphragm and normally penetrates the puncture hole therein, the distension of the diaphragm due to gas pressure from within the container not only causes the puncture to open but also moves the diaphragm outwardly so that a thinner part of the tapered member passes through the diaphragm or the diaphragm is entirely beyond the outer end of this member, that is the member is no longer in the puncture hole. There is thus an ample opening through which the gas can escape. The container is again sealed when the diaphragm returns to its normal position. This return may, if desired, be assisted as in the construction described above by a spring arranged between the diaphragm and the outer cover or cap.

The pin or other pointed tapered member may be of any suitable shape as for example conical or spade-like, the latter if the diaphragm is provided with an incision, provided that in the case of a member which does not normally penetrate the diaphragm its end is sufficiently sharp either to pass through a pin-hole puncture or incision or to pierce a fresh hole in the diaphragm material. The member may be of metal or of sufficiently hard insulating material. In the case of electrolytic condensers, a metal member must be of aluminum or other film forming material or of a metal which does not harmfully react with or otherwise affect the electrolyte.

If desired, two or more pins may be so arranged as to penetrate the diaphragm at a corresponding number of points. These pins may all be fixed to or formed integral with an outer protective cap or cover or one or more pins may be attached to or formed integral with a spring or springs, the remaining pins being carried by the cover in a manner readily understood from the above. Alternatively, there may be one or more tapered members carried by the condenser structure such as the riser or supporting member or the like normally passing through the diaphragm with or without pins attached to or formed integral with the outer cap and/or springs.

It will be evident from the above that the invention is not limited to the specific details and arrangements of parts as shown herein for illustration, but that numerous embodiments and modifications of the underlying inventive idea may be resorted to in accordance with the broader scope and spirit of the invention as defined by the appended claims.

The specification and drawing are accordingly intended to be interpreted in an illustrative rather than a limiting sense.

I claim:

1. A vent for an electrolytic condenser or the like having a container subject to internal excess gas pressure, comprising a diaphragm of elastic material, an arched apertured cap overlying said diaphragm, said diaphragm and cap being secured to an opening of said container with the outer portion of said diaphragm forming a sealing gasket between said cap and said container, the mid-section of said diaphragm being of lesser

thickness than its outer portion and having a puncture hole therein normally closed by reason of the elasticity of the material, an annular collar surrounding said mid-section and projecting towards said cap, a coil spring positioned to have its opposite ends engaging said mid-section and said cap, respectively, and a pointed member extending inwardly from said cap through said spring and arranged to engage said puncture hole during the distension of said diaphragm.

5 2. A vent for an electrolytic condenser or the like having a container subject to internal excess gas pressure, comprising a diaphragm of elastic material, an arched apertured cap overlying said 15 diaphragm, said diaphragm and cap being secured to an opening of said container with the outer portion of said diaphragm forming a sealing gasket between said cap and said container, the mid-section of said diaphragm being of lesser 20 thickness than its outer portion and having a puncture hole therein normally closed by reason of the elasticity of the material, an annular collar surrounding said mid-section and projecting towards said cap, a coil spring positioned to have 25 its opposite ends engaging said mid-section and said cap, respectively, and a pointed member extending inwardly from said cap substantially at right angle to said mid-section and having its point in line with and normally engaging the outer end of said puncture.

30 3. A vent for an electrolytic condenser or the like having a container subject to internal excess gas pressure, comprising a diaphragm of elastic material, an arched apertured cap overlying said 35 diaphragm, said diaphragm and cap being secured to an opening of said container with the outer portion of said diaphragm forming a sealing gasket between said cap and said container, the mid-section of said diaphragm being of lesser 40 thickness than its outer portion and having a puncture hole therein normally closed by reason of the elasticity of the material, an annular collar surrounding said mid-section and projecting towards said cap, a coil spring positioned to have 45 its opposite ends engaging said mid-section and said cap, respectively, and an extension of said coil spring bent radially and axially to provide a pointed member in line with and arranged to engage said puncture hole during the distension 50 of said diaphragm.

4. A vent for an electrolytic condenser and the like having a container subject to internal excess gas pressure comprising a diaphragm of elastic material, a cap overlying said diaphragm, said 55 diaphragm and cap being secured to an opening of the container, said diaphragm having a puncture normally closed by reason of the elasticity of the material and adapted to be opened by outward distension of the diaphragm under the action of a predetermined gas pressure developed within the container, and a coil spring arranged with its opposite ends engaging said diaphragm and cap, respectively, and having a pointed extension arranged axially thereof and in line with 60 said puncture.

5. A vent for an electrolytic condenser or the like having a container subject to internal excess gas pressure, comprising a diaphragm of elastic material, a cap overlying said diaphragm, said 70 diaphragm and cap being secured to an opening of said container, said diaphragm having a puncture normally closed by reason of the elasticity of the material and adapted to become opened by outward distension of the diaphragm under action of a predetermined excess gas pressure de-

veloped within said container, a resilient spacing member intervening between the distending portion of said diaphragm and said cap, said member consisting of a material having a more permanently maintained elasticity than said diaphragm and being provided with a pointed projection arranged to engage said puncture.

6. A vent for an electrolytic condenser or the like having a container subject to internal excess gas pressure comprising a diaphragm of elastic material, a cap overlying said diaphragm, said diaphragm having a puncture normally closed by reason of the elasticity of the material and adapted to become opened by outward distension under the action of a predetermined excess gas pressure developed within the container, and a resilient spacing member intervening between the distending portion of said diaphragm and said cap and having a more permanently main-

tained elasticity than said diaphragm, said resilient member having a pointed projection arranged to engage said puncture.

7. A vent for an electrolytic condenser or the like having a container subject to internal excess gas pressure comprising a diaphragm of elastic material, a cap overlying said diaphragm, said diaphragm having a puncture normally closed by reason of the elasticity of the material and adapted to become opened by outward distension under the action of a predetermined excess gas pressure developed within the container, and a coil spring having a more permanently maintained elasticity than said diaphragm and arranged with its opposite ends engaging the distending portion of said diaphragm and said cap, respectively.

JAMES HENRY COTTON.
